A. BOYNTON

POLISHED ROD ROTOR

Filed June 29, 1926

Patented June 21, 1927.

1,633,064

UNITED STATES PATENT OFFICE.

ALEXANDER BOYNTON, OF SAN ANTONIO, TEXAS.

POLISHED-ROD ROTOR.

Application filed June 29, 1926. Serial No. 119,329.

This invention relates to polished rod rotors for use in rotating the movable parts such as the polished rod, the sucker rod and the cups or plunger of a well pump.

More specifically the invention forming the subject of this application is in the nature of an improved actuating means for a rotor, through the medium of which, the rotor may be expeditiously adjusted for use in connection with pumping beams of various widths.

A further and equally important object of the invention is to provide a novel form of actuator by means of which the necessary motion is efficiently transmitted from the attaching base of the rotor to the clutch mechanism of the rotor.

Another object of the invention is to provide a pump accessory of the character specified which is of highly simplified construction, cheap to manufacture and one which is adaptable for use under a variety of conditions.

Other objects and advantages will be apparent during the course of the following description.

In the accompanying drawing forming a part of this application and in which like numerals are employed to designate like parts throughout the same.

Figure 1 is a perspective of the improved pumping accessory applied;

Figure 2 is a group perspective of the accessory detached;

Figure 3 is a vertical sectional view illustrating the manner in which the base plate of the accessory may be adjusted for use in connection with beams of various widths;

Figure 4 is a horizontal sectional view through the actuator and the arm thereof;

Figure 5 is a side elevation illustrating a slight modification of the invention.

In the drawing numeral 5 designates the beam of a jack known in the industry as an Oklahoma jack and which as suggested in Figure 1 consists of a pair of spaced parallel channel beams having their flanges extended outwardly. This, however, forms no part of this invention and is referred to merely to provide a basis for the statement that

the beams are not always of the same width or of the same cross sectional formation and the invention forming the subject matter of this application is intended to provide simple mechanical means whereby the base plate of a rotor may be economically pro-

duced for application to beams of various widths.

In carrying out the invention, I provide a base plate consisting of main sections 6 and 7, the outer portions of which are provided with downwardly and inwardly projecting ribs or flanges 8 and 9, respectively, to extend about and engage the laterally projecting flanges of the beam, all of which is clearly shown in Figure 1.

The inner portion of the section 6 of the base plate is offset so that the same may overlap and rest upon the section 7 in the manner shown in Figure 1 and is formed with an elongated slot 11, the wall of which is raised as shown at 12 to strengthen and reinforce the inner portion of the section 6. In addition to strengthening and reinforcing the inner portion of the section 6, the raised rib 12 provides a generous bearing surface for the upwardly extending boss 14 of the section 7.

Inspection of Figures 1 and 2 will clearly show that the boss 14 is adapted to be extended through the slot 11 and the laterally projecting oppositely located ears 16 positioned above the shoulder 12. This holds the parts loosely together preparatory to their application to the beam and therefore greatly simplifies the installation of the rotor.

When the base has been properly positioned on the beam the set screw 20 threaded through one end of the section 6 is tightened and by reason of the engagement of the set screw with the boss 14 the section 7 is moved inwardly so that both the attaching ribs 8 and 9 will be firmly engaged with the adjacent flanges of the beam. Figures 1 and 3 clearly illustrate that what might be said to be the outer side of the boss 14 is vertically grooved for the reception of the inner portion of the set screw 20. By making the opening 11 elongated the base is capable of a wide variety of adjustment and may be applied to any beam within very generous limits. This makes the manufacture of a number of sizes of base plates for use in connection with different size beams unnecessary.

Figures 2 and 3 illustrate that the outer side of the section 7, or more specifically that side of the section 7 opposite the slot 24 is laterally extended to define a shelf or track upon which the adjacent portion of the section 6 rests to overcome any tendency

of the section 7 to tilt when the screw 20 is tightened. As the set screw 20 applies pressure to the boss 14 above the central line of the gripping strain a generous contact surface is desirable between the outer portion of the section 7 and the slotted portion of the section 6.

Figure 2 illustrates that the flanged end 8 of the section 6 is split or divided for lightness and to provide a two point pull, which points are directly opposite the spaced flanges 9. By thus providing a two point pull at each side of the beam and providing a generous contact area between the outer portion of the section 7 and the adjacent portion of the section 6, the parts will remain in place and the tendency of the section 7 to tilt as a result of screw pressure will be overcome, whereby the flanges 8 and 9 may remain firmly in engagement with the laterally projecting flanges of the beam.

In carrying out the invention the casting 6 may be recessed or webbed as indicated at 4 for lightness and economy.

The hollow boss 14 is adapted to receive the cylindrical lower end of an actuator designated by the numeral 22. In applying the actuator 22 to the boss 14, the flat shank of the same is extended through an L-shaped slot 24 in the section 7 and the boss 14 and the flat shank is then moved upwardly so that the cylindrical bearing portion of the actuator will be properly received in the boss. The actuator is preferably cast in a single piece, and it will be seen that the connection between the flat shank of the same and the cylindrical lower end is stoutly braced and that the shank increases in width toward the lower end thereof, so that the same is amply able to withstand the strain incident to use.

The upper portion 32 of the actuator is somewhat circular in elevation and is provided with a cylindrical opening for the reception of the disk shaped terminal portion 33 of an actuating arm 34, all of which is clearly shown in Figure 1. Figure 4 clearly shows that the disk shaped terminal portion 33 is provided with arcuate ribs 36, one of which has sliding contact with the offset web 37 at one side of the head 32 and the other arcuate rib being extended into and engaged with the offset intermediate portion of a latch designated by the numeral 40.

In carrying out the invention, the latch 40 is pivoted to one side of the head 32 and is provided with a U-shaped yoke engaging member 44 by means of which the disk shaped member 33 is held within the head 32. However, the disk shaped terminal portion 33 may partake of a limited turning movement in the head 32, which turning movement is necessary and desirable to the efficient operation of the rotor. This turning movement is essentially about a hori-

zontal axis. In this connection it is noted that the rocking of the disk shaped terminal portion 33 is confined to a horizontal axis as other movement such as lateral movement is avoided by the provision of the arcuate ribs 36 and the parts engaged thereby.

It is believed to be sufficient to close this description of the structure of this invention by adding that the arm 34 is connected at one end with a trunnion nut 48 and that the trunnion nut is mounted on the trunnion 49 of a clutch mechanism 50, forming no special part of the invention herein disclosed.

In summarizing, it will be seen that when it is desired to install the improved pumping accessory, it is merely necessary to extend the flat shank of the actuator through the slot 24 in the boss 14 and then turn the actuator to the position illustrated in Figure 1. When the actuator is thus extended through the boss, the flange 62 on the lower end of the actuator will be snugly received in the rabbeted lower end of the opening in the boss 14 whereby further upward movement of the actuator is prevented.

With the actuator thus extended through the boss 14, it is a simple matter to attach the sections 6 and 7 to the beam and then tighten the set screw 20 to anchor the base firmly in place. It is important to note that when the actuator is attached to the boss 14, it may easily partake of the limited turning resulting from the oscillation of the beam. In this connection it is noted that the lubrication of the lower portion of the actuator and the boss 14 is greatly simplified by the provision of the L-shaped slot 24.

Expressed in other words, the back and forth movement of the arm 34 results in a slight turning of the actuator in the boss 14 and by providing the slot 24, a suitable lubricant may be easily supplied to the interior of the boss. Particular attention is directed to the fact that the actuator can not be held against the necessary free movement through mal-adjustment.

In the form of invention illustrated in Figure 4 the base plate consists of a pair of sections 70 and 71 adapted to be connected in the same manner as are the sections 6 and 7, and it will be seen that the sections are provided with curved depending attaching arms 75 adapted to engage the circular sections of a beam. This form of invention is especially adapted for use when the beam is made up of a plurality of pipe sections or the like.

Having thus described the invention, what is claimed is:

1. A base plate for polished rod rotors comprising a pair of sections having beam engaging means, one of the sections overlapping the other section, the section which is overlapped being provided with a boss extending through the overlapping portion

- of one of the sections and adapted to receive the actuator of a rotor.
2. A base plate for polished rod rotors comprising a pair of sections having beam engaging means, one of the sections overlapping the other section, the section which is overlapped being provided with a boss extending through the overlapping portion of one of the sections and adapted to receive the actuator of a rotor, said boss being slotted for the passage of the shank of an actuator therethrough. 65
3. An attaching base for polished rod rotors comprising a pair of sections having beam engaging means, one of which is formed with a slot, the other section being provided with a boss detachably extended through said slot. 70
4. An attaching base for polished rod rotors comprising a pair of sections having beam engaging means, one of which is formed with a slot, the other section being provided with a boss detachably extended through said slot, and means carried by said boss to hold the sections together preparatory to the application of the same to a beam. 75
5. An attaching base for polished rod rotors comprising a pair of sections having beam engaging means, one of which is formed with a slot, the other section being provided with a boss detachably extended through said slot, and means carried by said boss to hold the sections together preparatory to the application of the same to a beam, said boss and the associated sections of the same being provided with a passage for the shank of an actuator. 80
6. An attaching base for polished rod rotors comprising a pair of sections having beam engaging means, one of which is formed with a slot, the other section being provided with a boss detachably extended through said slot, and means carried by said boss to hold the sections together preparatory to the application of the same to a beam, said boss and the associated sections of the same being provided with a passage for the shank of an actuator, and means whereby said sections may be moved into locking engagement with a beam. 85
7. An adjustable attaching base for a polished rod actuator comprising a pair of sections, one of which is provided with an inner portion overlapping the other section and having an elongated slot, a boss extending upwardly from one of the sections and extending through said slot, said boss being provided with ears adapted to be positioned above the slotted inner portion of one of the sections, a set screw carried by the slotted inner portion of one of said sections and adapted for engagement with said boss whereby the sections may be forced into locking engagement with a beam. 90
8. An adjustable attaching base for a polished rod actuator comprising a pair of sections, one of which is provided with an inner portion overlapping the other section and having an elongated slot, a boss extending upwardly from one of the sections and extending through said slot, said boss being provided with ears adapted to be positioned above the slotted inner portion of one of the sections, a set screw carried by the slotted inner portion of one of said sections and adapted for engagement with said boss whereby the sections may be forced into locking engagement with a beam, said boss being adapted to rotatably receive an actuator and having means to limit upward movement of the actuator. 95
9. The combination of a base having a pair of sections, one of which has an opening, an actuator rotatably extending through said opening and adapted to rest upon a pumping beam, the wall of said opening being provided with means to limit upward movement of the actuator. 100
10. The combination of an actuator having a head provided with a socket having one end open and an offset web at one side of said opening, and an arm having a terminal portion received in said opening and having arcuate ribs, one of which is engaged with said web, and a latch connecting said head and said arm and engaged by one of said ribs. 105
11. The combination of a pair of members, one of which has a socket opened at one end, the other member being provided with a terminal portion received in said socket and adapted to partake of a limited rocking movement therein, a latch detachably holding said terminal portion in the socket, and means to limit lateral movement of one member with respect to the other. 110
12. The combination of a pair of members, one of which has a head provided with an opening and a web, the other member being provided with a terminal portion received in said opening and having laterally projecting ribs, one of which is engaged with said web, and a latch connecting the members and having an offset portion receiving the other rib. 115

In testimony whereof I affix my signature.

ALEXANDER BOYNTON.
